UNITED STATES PATENT OFFICE

2,614,421

APPARATUS FOR MEASURING AND ADJUSTING THE SPRING PRESSURE ON COMMUTATOR BRUSHES

Martin Culkosky, Gary, Ind.

Application June 23, 1948, Serial No. 34,628

3 Claims. (Cl. 73—161)

1

This invention relates to apparatus for adjusting and measuring the spring pressure on commutator brushes and is a continuation-in-part of my copending application, Serial No. 625,577, filed October 30, 1945, now Patent No. 2,471,480, patented May 31, 1949.

The amount of pressure by which brushes, such as shown in my copending application, are held in contact with the commutator is very important. In order to avoid unequal distribution of current among the different brushes on the machine, it is necessary that the pressure be equal on all brushes. There is also a limited range of pressure within which best brush performance is obtained. If the pressure is too light, imperfect contact with the commutator is liable to result, causing sparking, injury to the commutator surface and undue brush wear. Excessive brush pressure results in unnecessary friction, needless wear and may even reduce the stability of the brush position in its holder and against the commutator.

It is therefore an object of my invention to provide apparatus for adjusting and measuring the spring pressure on all brushes so that the brush pressure on the slip ring or commutator can be uniform.

This and other objects will be more apparent after referring to the following specification and attached drawings, in which:

Figure 1 is a side elevation, partly in section, of my device; and

Figure 2 is a top plan view of Figure 1.

Referring more particularly to the drawings, the reference numeral 2 indicates an insulated brush holder support mounted on the motor frame (not shown). Attached to the support 2 by means of the bolts 4 is a brush holder 6. The holder 6 has an elongated body member 8 with a pair of spaced apart brush receiving openings 10 therein. Between the openings 10 is a pair of spaced apart lugs 12 for receiving a hub 14 which is held in place by means of screw 16. The hub 14 is provided with tapped holes 17 for receiving screws 18 which hold a brush arm 20 in place over the openings 10. A tap 22 on each end of the arm extends toward the adjacent opening 10. Located in each of the openings 10 is a brush 24 having a circular inner portion 26 for bearing against the slip ring 28. A recess 30 is provided in the center of each brush on the side facing the tap 22. A button-head base 32 having a reduced portion 34 extending toward the tap 22 is located in the opening 30. The base 32 is made of fiber or any other suitable dielectric material. The tap

22 is centrally located over the base 32 and a spring 36 surrounds the tap and reduced portion 34 of the base. The base 32 in addition to insulating the spring from the brush assures a firm even contact between the brush 24 and the spring 36. With this construction the brush 24 contacts the ring 28 throughout the surface 26 and no air gap is formed. Wires 38 are connected to the brush in the usual manner and are fastened to the body member 8 by means of a screw 40. A feed line 42 is connected to the body member 8 by means of a screw 44.

The apparatus so far described is that shown in my above mentioned copending application.

According to the present invention, at least one of each pair of bases associated with each brush arm 20 is provided with a tapped opening 46. In that portion of the arm 20 directly above the base 32 is a threaded opening 48 for receiving an adjusting screw 50 having the tap 22 mounted thereon. A lock nut 52 is provided for locking the adjusting screw in position. The adjusting screw 50 is provided with an axial opening 54. An I-screw 56 passes through the opening 54 and is threaded into the opening 46. A spring gauge 58 is provided with a hook 60 which is received in the eye of the bolt 56.

The method of adjusting the brush pressure is as follows:

The I-bolt 56 is threaded into the opening 46 and the spring gauge 58 is attached thereto as shown. A pull is then exerted on the spring gauge 58 until the spring 36 is compressed and the base 32 is removed slightly from its seat. Since the spring 36 and spring gauge 58 oppose each other, the spring 36 will be carrying the same load as the spring gauge 58. Since the lever arm between the pivot point 16 and the center of each of the pairs of brushes is equal, the pressure on each spring 36 will be equal. In this manner the pressure on each of the springs 36 is determined. When it is desired to adjust spring pressure to a certain amount, as for example, 2 pounds, the adjusting screw 50 is turned to increase or decrease the pressure on the spring 36 until the pressure on gauge 58 will read 2 pounds when the base 32 is just removed from its seat. In this manner the spring pressure on each of the brushes 24 is adjusted to the desired amount by making one adjustment. This process is repeated for each pair of brushes until all the brush pressures are uniform.

In some instances the brushes are not arranged in pairs, as shown, but each brush has its own individual brush arm. In such a case the brush

arm is provided with a threaded opening 48 and adjusting screw 50 as shown and the method of adjustment will be the same as that described above except that the pressure on each brush must be adjusted and determined separately.

While one embodiment of my invention has been shown and described, it will be apparent that other adaptations and modifications may be made without departing from the scope of the following claims.

I claim:

1. Measuring apparatus for use with a motor brush holder having a body member with a brush receiving opening therein, a brush in said opening, a brush arm attached to said body member and extending over said opening, a base bearing against said brush, said base having an axial threaded opening therein, said arm having a threaded opening therethrough in axial alignment with the first named axial opening, a bushing in said second named opening, said bushing having an axial opening therethrough, and a spring extending between said base and said bushing; which apparatus comprises a bolt extending through the bushing into the threaded opening in the base, and a tension indicating means fastened to the free end of said bolt.

2. Apparatus of the kind described comprising a commutator brush bearing against the slip ring of a motor, a brush arm, a bushing adjustably mounted in said brush arm in alignment with said brush, a base bearing against the brush, said base having an axial threaded opening therein, a spring extending between said bush-

ing and said base, the bushing being formed with an axial opening whereby a bolt may be secured in the threaded opening and a tension indicating means fastened to the free end of said bolt.

3. Apparatus of the kind described comprising a pair of commutator brushes bearing against the slip ring of a motor, a brush arm extending from a pivot an equal distance to a position over each brush, a spring extending between one end of said brush arm and one of said brushes, a bushing adjustably mounted in the other end of said brush arm in alignment with the second of said brushes, a base bearing against the second brush, said base having an axial threaded opening therein, a spring extending between said bushing and said base, the bushing being formed with an opening whereby a bolt may be secured in the threaded opening and a tension indicating means fastened to the free end of said bolt.
